PORTRABLE HOIST

Stephen J. Hoff, Richmond, Ind., assignor to Hoffco,
Inc., Richmond, Ind., a corporation of Indiana

Filed Oct. 17, 1963, Ser. No. 77,013

Term of patent 14 years

(Cl. D41—1)

FIG. 1 is a perspective view of a portable hoist embodying my new design;

FIG. 2 is a front elevational view thereof with the hooks and cable and handle removed for convenience of illustration;

FIG. 3 is a right side elevational view thereof;

FIG. 4 is a rear elevational view;

FIG. 5 is a bottom plan view; and

FIG. 6 is another perspective view showing a modified form, the difference residing in the handle member as shown.

The dominant features of my design reside in the portions shown in solid lines, the broken line showing of the hooks and cable being for illustrative purposes only.

This application is a continuation-in-part of my copending and now abandoned application Serial No. D. 72,962, filed December 26, 1962.

I claim:

The ornamental design for a portable hoist, as shown and described.
